MANIFOLDING UNIT

Louis Huffman, Toronto, Ontario, Canada, assignor to Toronto Type Foundry Company, Limited, Toronto, Ontario, Canada

Application January 11, 1933, Serial No. 651,099

8 Claims. (Cl. 282—9)

This invention relates to improvements in manifolding forms wherein clean record leaves are so arranged with respect to a transfer leaf or leaves in each manifolding unit of the form that the form may be manipulated to inscribe a writing on the record leaves of the unit, to detach the removable record and transfer leaves following use and to prepare the succeeding unit for an inscription, without soiling the hands of the operator or soiling any material or object with which the form might come into contact.

The invention is adaptable to manifolding forms whatever may be the number of record copies produced by each unit and whatever may be the relative arrangement or connection of the several units which make up the form, whether books, cut forms, fanfolds, or the like.

I attain the object of my invention by providing record leaves and a transfer leaf or leaves so constructed and associated together in each unit of the form that all the manipulations required to work the form may be accomplished without contact with or exposure of a transfer surface of the transfer leaf or leaves.

In a duplicate form a preferred arrangement consists in the provision of clean surfaced original and duplicate record leaves connected together by an intervening transfer leaf having transfer material on the side adjacent to the duplicate record leaf only, the relative arrangement being such that the transfer coated surface of the transfer leaf is not exposed to contact outside of the form during manipulation thereof.

In a triplicate form a single transfer leaf, coated with transfer material on both sides, may be used, and the connection between the original record leaf and the triplicate record leaf may be through a translucent record leaf normally overlying one transfer surface of the transfer leaf, the arrangement being such that the several manipulations required to work the form may be accomplished without contact with or exposure of either transfer surface of the transfer leaf.

If the arrangement is in the form of a duplicate book the original record leaf may be removed following use and the transfer leaf and duplicate record leaf thrown back to expose the succeeding unit without contact with or exposure of the transfer surface of the transfer leaf and the transfer leaf may then be detached, or it may be detached later at the leisure of the operator together with a number of other used transfer leaves, without contact being made with or exposure of its transfer surface.

If the arrangement is in the form of a triplicate

book or in any other fashion, the same desirable objects may be accomplished, due to the particular construction and arrangement as herein-after more specifically set forth.

The invention is hereinafter more specifically described and is illustrated in the accompanying drawing in which

Fig. 1 is a perspective view of a single manifolding unit including two record leaves;

Fig. 2 a perspective view of a hook made up of a plurality of units such as shown in Fig. 1; and

Figs. 3 to 5 perspective views of modifications of the invention.

In the drawing like numerals of reference indicate corresponding parts in the different figures.

In the simplest form a unit comprises three connected leaves 1, 2 and 3 folded in zigzag form. Leaf 1 forms an original record, leaf 2 is a transfer leaf carbonized on its under side and leaf three is a duplicate record to which entries on the original are transferred by the leaf 2. The leaf 3 is shown as provided with a stub 4 delimited by the line of weakness 5. (See Fig. 1.)

If the units are to be used as what are known as cut forms the stubs 4 may be punched in order that they may be filed on post binders.

To form a book a suitable number of the forms will be bound to a cover of ordinary construction as shown in Fig. 2. This cover comprises the back 6, top cover leaf 7 and stop leaf 8, having the usual functions.

When a unit is used in a book or in sets of cut forms the bottom of each original record leaf 1 will be the end remote from the stub.

The method of using the unit will be obvious, whether as a cut form, fanfold or in a book. Any entry made on the original record leaf is transferred to the duplicate record leaf by the transfer leaf. After the original has been torn off, the transfer leaf remains attached to the duplicate leaf with its transfer surface hidden. If the unit is being used in a book the leaves 2 and 3 are then grasped at their joined ends and thrown back against the front cover to expose the original of the next unit which is ready for use as soon as the stop leaf 8 has been repositioned under the new top unit.

In these operations no carbonized surface is contacted by the hands. The transfer leaf may be left attached to the duplicate or may be removed at any time.

The three leaves may be formed of an integral sheet of paper but, as it is usual to make the transfer leaf of a special thin paper, it will gen-

erally be preferable to use separate leaves adhesively secured together.

For this purpose and for cleanliness in handling the transfer leaf will usually be formed with 5 uncarbonized margins both back and front at each end.

To facilitate separation of the original from the duplicate a line of weakness 11 is provided in the original below the part of its end adhered 10 or otherwise connected to the transfer sheet 2. In tearing off the original record leaf, the attached ends will be grasped by the fingers of one hand and the leaf torn off with the other. The under margin of the transfer leaf being clean 15 the fingers grasping it are not soiled.

To facilitate the separation of the duplicate from the transfer leaf a line of weakness 12 is provided in the underlying duplicate above the part of its end attached to the transfer leaf. In 20 separating the transfer leaf from the record leaf the attached margins of the record leaf and transfer leaf are grasped with one hand while the underlying record leaf is held down, adjacent the stub, by the other hand, when a tearing movement 25 will separate the record leaf on the line of weakness leaving its margin attached to the transfer leaf.

The transfer leaf thus has attached to it the upper margin of the original leaf and the lower 30 margin of the duplicate, leaving both record leaves free of attached fragments.

A triplicate book embodying my invention is readily made by the addition of one leaf.

It is possible, of course, to make three of the 35 leaves from a single sheet of paper, but usually it will be preferable to use separate leaves adhesively secured together as thus the preferred quality of paper may be used for each type of leaf.

In Fig. 3 I show a triplicate book in which the 40 original leaf 1 is connected with the upper end of the double sided transfer leaf 2, which is attached with the translucent leaf 9 to the lower end of the leaf 3. The transfer leaf forms the hinge connecting the two record leaves. This 45 transfer leaf 2 is carbonized on both sides and transfers to the upper surface of the record leaf 3 and to the underside of the translucent leaf 9. In this form the original record leaf is provided with a line of weakness 10 along which it may be 50 separated from the transfer leaf 2, which transfer leaf may remain with the record leaf 3. When this unit is used in the book and the transfer leaf 2 is permitted to remain with the record leaf 3 the two leaves 2 and 3 will be readily thrown 55 back together as in the handling of the duplicate book illustrated in Figs. 1 and 2. To the above extent the construction of Fig. 3 is similar to the construction shown in Figs. 4 and 5. Figs. 4 and 5 are variants of Fig. 3, however, as hereinafter described.

In Fig. 4 a further variant is shown, the leaves 1, 9 and 2 being connected at their upper ends, while the leaf 2 is connected at its lower end to the lower end of the leaf 3.

In Fig. 5 a variant is shown in which the upper 65 ends of the leaves 1 and 2 are connected and the lower ends of the leaves 2 and 3, while the leaf 9 has its lower end connected to the lower end of the leaf 1.

In all forms the several manipulations required 70 to work the form may be effected without contact with or exposure of either transfer surface of the transfer leaf.

While I have shown preferred embodiments of 75 my invention numerous modifications are possible

which would fall within the scope of my invention.

What I claim as my invention is:

1. A manifolding unit comprising a record leaf; a transfer leaf connected to the bottom end of the record leaf and normally overlying the record leaf; a second record leaf normally overlying the transfer leaf and connected by one end to the upper end of the transfer leaf; and a translucent record leaf connected to the upper end of the second record leaf overlying the transfer leaf. 10

2. A manifolding unit including two opaque clean surfaced record leaves, one of which is the original record leaf, a transfer leaf connecting said two opaque record leaves together in zigzag 15 formation, and a translucent record leaf connected in the unit between the original record leaf and the transfer leaf.

3. A manifolding unit including two opaque clean surfaced record leaves, one of which is the 20 original record leaf, a transfer leaf connecting said two opaque record leaves together in zig-zag formation, said original record leaf having a weakened line of severance spaced inwardly from the end connected to the transfer leaf 25 sufficiently to form a finger grip, the side of the transfer leaf remote from the record leaf and adjacent the line of connection with the record leaf being free of transfer material.

4. A manifolding unit comprising two opaque 30 clean surfaced record leaves, one of which is the original record leaf, and a transfer leaf connecting said two opaque record leaves together in zigzag formation, each record leaf provided with 35 a weakened line of severance spaced from the end connected with the transfer leaf sufficiently to form a finger grip, the side of the transfer leaf remote from the record leaf and adjacent the line of connection with the record leaf being 40 free of transfer material.

5. A manifolding unit comprising a record leaf, a transfer leaf connected to one end of the record leaf and overlying the record leaf, a second record leaf connected to the opposite end of the transfer leaf, and a translucent record leaf connected at one 45 end to the first record leaf and overlying the transfer leaf underneath the second record leaf.

6. A manifolding unit comprising a record leaf, a transfer leaf connected to one end of the record leaf and overlying the record leaf, a second record leaf connected to the opposite end of the transfer leaf and overlying the transfer leaf, and a translucent record leaf connected at one end to the free end of the second record leaf and overlying the transfer leaf underneath the second record leaf. 55

7. A manifolding unit comprising a record leaf, a transfer leaf connected to one end of the record leaf and overlying the record leaf, a second record leaf connected to the opposite end of the transfer leaf and overlying the transfer leaf, and a translucent record leaf connected at one end to an end of one of the record leaves and overlying the transfer leaf underneath the second record leaf. 60

8. A plurality of manifolding units arranged in superposed relationship, each unit comprising a plurality of clean surfaced record leaves 70 and a transfer leaf interleaved and connected together in the unit, three of said leaves being arranged in zigzag form and one of the record leaves having the transfer leaf attached thereto, said record leaf provided with a weakened line 75

5 of severance extending thereacross spaced from the line of attachment of the transfer leaf therewith, the said transfer leaf having an uncarbonized margin on its face remote from the record leaf and adjacent the line of attachment with the record leaf, whereby the margin of the transfer leaf and the part of the record leaf between

the line of attachment and the line of severance may be gripped to detach the transfer leaf, with the part of the record leaf to which it is attached, along the line of severance without contact with the carbonized surface of the transfer sheet.
